TROT LINE REEL

Ivan H. Moore, 1405 Pfister Drive,
Coffeyville, Kans. 67337

Filed Mar. 20, 1967, Ser. No. 6,307

Term of patent 14 years

(Cl. D22—22)

FIG. 1 is a side elevation of a trot line reel embodying my new design, the broken line base support members are broken away for ease of illustration;

FIG. 2 is a top plan view of my design in FIG. 1; and

FIG. 3 is a perspective view of the trot line reel without any hooks or lines shown thereon.

The undisclosed portions of the trot line reel are substantially the same in appearance as the sides shown in FIGS. 1 and 3.

The dominant features of the design reside in the portions shown in solid lines.

I claim:

The ornamental design for a trot line reel, as shown and described.
